SUPPORT STANDARD FOR SHELVING

Eugene Brown, Rockville Centre, N.Y., assignor to
Barclay Industries, Inc., Lodi, N.J.

Original design application Feb. 25, 1972, Ser. No.
229,622, now Patent No. 231,295. Divided and
this application Feb. 14, 1974, Ser. No. 442,475

Term of patent 14 years

Int. Cl. D6—06

U.S. Cl. D6—114

FIG. 1 is a front elevational view of a support standard for shelving, showing my new design;

FIG. 2 is a front elevational view of a second embodiment thereof, viewed in the direction of arrows 2 of FIG. 3;

FIG. 3 is a side elevational view thereof, the opposite side being a mirror image thereof.

The side elevational view of the first embodiment is understood to be substantially the same in appearance as the side elevational view of the second embodiment, with allowance being made for the differing number of units.

The rear of all embodiments of the standard is unornamented.

This is a division of Ser. No. 229,622, filed Feb. 25, 1972, now Design Pat. 231,295.

I claim:

The ornamental design for a support standard for shelving, as shown.
